US00D848869S

(12) United States Design Patent (10) Patent No.: US D848,869 S
(45) Date of Patent: * May 21, 2019

(54) CARPET CUTTING TEMPLATE

(71) Applicant: ITEL Laboratories, Inc., Jacksonville, FL (US)

(72) Inventors: Steve M. Alvarez, Jacksonville, FL (US); Chris A. Touchton, Jacksonville, FL (US)

(73) Assignee: ITEL Laboratories, Inc., Jacksonville, FL (US)

() Term: 15 Years

(21) Appl. No.: 29/557,573

(22) Filed: Mar. 10, 2016

(51) LOC (11) Cl. 10-04

(52) U.S. Cl.

USPC D10/64

CLAIM

The ornamental design for a carpet cutting template, as shown and described.

DESCRIPTION

FIG. 1 is a perspective view of the carpet cutting template, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the article that form no part of the claimed design. The dash-dot broken lines represent the bounds of the claim that form no part of the claimed design.

1 Claim, 5 Drawing Sheets
